DRAFT RIGGING

Donald S. Barrows, Rochester, N. Y., assignor to
 The Symington Company, Rochester, N. Y., a
 corporation of Maryland

Application April 22, 1932, Serial No. 606,988

12 Claims. (Cl. 213—7)

This invention relates to draft rigging particularly adapted for tenders where it is desired to have increased capacity for the absorption of draft forces as compared with the capacity for the absorption of buffing forces.

The principal object of my invention, generally considered, is to provide, in combination with a railway vehicle underframe a friction draft mechanism or gear preferably comprising elements operating in series and enclosed in a housing or shell having means for connecting said shell to associated longitudinal members of the vehicle underframe so that the shell is held stationary on buff, to prevent the actuation of a portion of the cushioning mechanism therein, while allowed to move forwardly on draft, so that all of said cushioning mechanism is then actuated for the absorption of relatively large forces as, for example, when a connected locomotive is accelerating a train.

Another object of my invention is the provision of railway draft rigging including a cushioning device comprising a housing or casing open at both ends and receiving friction elements and resilient means associated therewith for urging said elements into engagement with said casing at each end, said device being mounted between longitudinal framing members of a railway vehicle, which members are provided with stops engaging portions of said housing to prevent rearward movement thereof and corresponding actuation of the rearward friction members and resilient means on buff, yoke-acting means being provided for pulling the rear cushioning elements and housing forwardly on draft to thereby actuate all of said mechanism.

Other objects and advantages of the invention relating to the particular arrangement and construction of the various parts will become apparent as the description proceeds.

Referring to the drawings illustrating my invention:—

Figure 1 is a vertical longitudinal sectional view between the sills or longitudinal draft portions of a railway vehicle or tender underframe illustrating one embodiment of my invention.

Figure 2 is a fragmentary horizontal sectional view of the mechanism shown in Figure 1, certain portions being shown in plan.

Figure 3 is a fragmentary transverse sectional view on the line 3—3 of Figure 2, looking in the direction of the arrows.

Figure 4 is a fragmentary transverse view on the line 4—4 of Figure 2, looking in the direction of the arrows.

Figure 5 is a fragmentary view corresponding to Figure 1, but showing a modification.

Figure 6 is a fragmentary view like Figure 2, but showing a further modification.

Referring to the drawings in detail, like parts being designated by like reference characters, and first considering the embodiment of my invention illustrated in Figures 1 to 4, inclusive, there are shown portions of an underframe which are particularly suitable for use on a tender. 5 Such underframe, in the present embodiment, is shown as of the cast type, comprising longitudinal draft members or arms 1 with an integral end sill or buffer block portion 2, and an integral sill tie or coupler carrier portion 3 normally supporting a carrier block 4 held in place by a retaining bolt, or the like 5. Intermediate portions of said sills or draft arms 1 are, in the present embodiment, connected by an integral transverse portion 6 which may be designated as a 10 backstop, although, in the present embodiment, it does not have all the usual backstop functions.

In the present embodiment, I have shown a draft gear or cushioning mechanism 7 disposed between the draft arms or longitudinal members 1 and comprising a housing 8 open at both ends and provided with inclined friction surfaces 9 normally engaged by wedge blocks 10 urged apart and into engagement with said inclined friction surfaces by curved plate springs 11. The housing 8 is formed with a slot 12 therethrough receiving a horizontal draft key 13, the ends of which pass through corresponding slots 14 in a yoke or yoke-acting means 15 and are received in corresponding slots 16 in the draft arm portions 1 of 25 the underframe. The slots 14 in the yoke 15 are elongated rearwardly of the normal position of the key 13 which desirably snugly fits the slot 12 in the housing 7, while the slots 16 in the draft members 1 are elongated forwardly of the normal 30 position of the key 13, a distance corresponding approximately to the normal movement for full compression of the friction elements comprising the front cushioning device, whereby said key 13 and its connected housing are permitted to move 35 forwardly on draft while held stationary on buff, the yoke being allowed to move forwardly not only with respect to the draft members 1, but also with respect to the housing 7. For properly supporting the housing between the draft members 1, carrier irons 17 and 18, with their ends supported from the lower flange portions 19 of the draft members 1, are provided.

A coupler 20, which, in the present embodiment, is illustrated as of the swivel butt type, is 50 55

provided and connected to the arms of the yoke 15 by a front key 21, the ends of which pass through slots 22 in the yoke arms and slots 23 in the sills or draft members 1 of the vehicle. 5 The slots 22 in the yoke arms are elongated rearwardly of the normal position of the key 21 to provide for the permissible rearward movement of the coupler 20 with respect to the sills 1, said movement being sufficient to compress the front half 10 of the draft gear 7. The slots 23 are elongated forwardly of the normal position of the key 21 an amount sufficient to allow for complete actuation of the gear 7, that is, both the front and rear mechanisms therein, said slots being elongated 15 rearwardly of the normal position of the key 21 an amount merely sufficient to allow for compression of the forward mechanism of the gear 7.

A front follower 24 is desirably associated with the front wedge blocks 10 of the gear 7 and is 20 normally in engagement with front stop portions 25 and 26 which, in the present embodiment, are integral with the draft portions 1 of the underframe. A rear follower 27 is desirably associated with the rear friction wedges 10 of the gear 7 25 and notched, as indicated at 28, to receive supporting lug or abutment portions 29 desirably extending forwardly from the backstop portions 6 into engagement with the rearmost edge of the housing 8. A tie member 30 desirably connects 30 the draft arm portions 1 above the gear 7. The yoke 15 desirably embraces the cushioning mechanism 7, the front and rear followers 24 and 27, extends between the upper and lower lugs 29, and normally engages the backstop 6, the front follower 24 being desirably supported from the yoke 35 as by means of shoulder portions 31 engaging the upper edge of said yoke.

The operation of my improved gear is as follows:—Under the action of draft forces, the coupler 20 pulls the yoke 15 forwardly by means of 40 a key 21, said yoke, in turn, acting on the rear follower 27 to force the friction members 10 into the housing 8 and simultaneously move the housing forwardly over the front friction elements 45 10 which are stopped by the front follower 24 in engagement with the front stops 25 and 26, whereby the full capacity of the gear is available for the cushioning of the large starting forces exerted by locomotives.

50 Under the action of buffing forces, the housing 8 is held stationary not only by the key 13 but also by the lugs 29 which engage the rear portion thereof, the coupler pushing the front follower 24 rearwardly and thereby forcing the front 55 friction elements 10 into the relatively stationary housing 8, utilizing only the cushioning capacity of the forward portion of the gear 7, thereby decreasing, to that extent, the slack between the tender and adjacent car, for example, when a 60 train is being stopped.

Referring now to the embodiment of my invention illustrated in Figure 5, a construction is there disclosed which is substantially identical with that of Figures 1 to 4, inclusive, except that instead of using a horizontal draft key extending 65 through a slot in the housing 8^a of the gear 7^a, said housing has shouldered portions 32 engaging a transverse tie portion 33 connecting the framing or sill portions 1^a of the underframe and 70 a transverse key member 13^a lying beneath the housing 8^a and with its ends received in corresponding slots 16^a in the sills 1^a. As in the previous embodiment, the housing 8^a receives friction wedges 10^a and curved plate springs 11^a at each 75 end, and is provided with a front follower 24^a,

normally engaging front stops 25^a and 26^a, and a rear follower 27^a, all of said elements being embraced by a yoke 15^a engaging a backstop portion 6^a and connected to a coupler (not shown) in a manner similar to that disclosed in the preceding embodiment. As in said preceding embodiment, the housing may be supported by carrier irons 17^a and 18^a.

The operation of the modified form of my invention disclosed in Figure 5 may be identical 10 with that of Figures 1 to 4, inclusive, the members 33 and 13^a functioning as the key 13 of the preceding embodiment for stopping the housing and preventing actuation of the rear cushioning portion of the gear on buff, while allowing the 15 housing to move forwardly with the development of full cushioning capacity on draft.

Referring now to the embodiment of my invention illustrated in Figure 6, a construction is there disclosed which is identical with the embodiment of Figures 1 to 4, inclusive, except that the lugs 29^b which extend forwardly from the backstop 6^b are notched to provide abutments 34 for the housing 8^b of the gear 7^b and extended forwardly of said abutments to lie on either side 25 of said housing to prevent sidewise shifting when the same is moved forwardly under the action of draft forces. As in the first embodiment, the key 13^b extends through the housing 8^b and has its ends received in slots 16^b in the sills 1^b, the slots 30 being elongated forwardly to allow for movement of the housing under the action of draft forces for the development of the full cushioning capacity of the gear 7^b. The portions of the embodiment of Figure 6 not illustrated correspond 35 with the showing in Figures 1 to 4, inclusive, as will be understood.

From the foregoing disclosure, it will be seen that I have devised an improved form of cushioning mechanism involving a housing open at 40 both ends to receive resiliently actuated friction members, said housing being mounted between the longitudinal elements of an underframe so that it is stationary with respect thereto against the action of buffing forces while movable under 45 the action of draft forces, so that the full cushioning capacity of the gear is developed for absorbing the relatively large shocks imparted from a locomotive tender, for example, in starting a train, the unnecessary capacity for the absorption of buffing shocks under such circumstances being reserved, with a corresponding decrease in train slack.

Although preferred embodiments of my invention have been illustrated, it will be understood 55 that modifications may be made within the spirit and scope of the appended claims.

I claim:—

1. In a railway vehicle, in combination with draft arms, a drawbar, a yoke, a friction draft gear 60 embraced by said yoke and comprising a housing member with open ends providing outwardly flaring friction surfaces, a set of friction elements engaging the friction surfaces at each end, resilient means disposed between said elements at each end 65 for holding them in engagement with said friction surfaces, a follower engaging the ends of said friction elements at each end of the gear, stop portions provided on said draft arms and normally engaged by said front follower, said rear 70 follower normally engaging said yoke and said yoke normally engaging a backstop portion connecting said draft arms, said backstop portion having abutment portions extending forwardly therefrom and normally engaging the rear edge 75

of said housing, whereby said housing and yoke are both held against relative movement when the gear is subjected to buffing forces.

2. In a railway vehicle, in combination with 5 longitudinal framing portions, a drawbar, yoke-acting means, a friction draft gear comprising a housing open at both ends, a set of friction elements received in each end of said housing, resilient means disposed between said friction elements for urging them into engagement with said housing, said yoke-acting means embracing said housing and friction elements, said housing being slotted between the sets of friction elements, and a key received in said slot, the ends of said key 10 extending through corresponding slots in said yoke-acting means and longitudinal framing portions, the slots in the yoke-acting means being elongated in only one direction and the slots in the longitudinal framing portions being elongated in only the other direction from the normal position of the key.

3. In a railway vehicle, in combination with slotted longitudinal framing portions, a drawbar, yoke-acting means, a friction draft gear comprising a column member, a set of friction elements cooperating with said member at each end, said yoke-acting means embracing said member and friction elements, said column member being slotted between the sets of friction elements, 20 and a key received in said slot and corresponding slots in said longitudinal members, said latter slots being elongated forwardly only from the normal position of the key.

4. In railway draft rigging, in combination with 25 a drawbar, sills each provided with a plurality of longitudinally spaced key slots, a draft gear comprising a plurality of cushioning devices enclosed in a housing mounted between said sills, yoke-acting means embracing said housing and cushioning devices and provided with key slots corresponding with the sill slots, a key extending through slots in the yoke-acting means and through forward slots of said sills to operatively connect the drawbar and yoke-acting means, and 30 a key through said housing and extending between said cushioning devices, entering the rearward slots in said sills, and serving to prevent actuation of the rear cushioning device on buff, said sills cooperating with said last-named key to 35 prevent rearward movement of the latter when the coupler is subjected to buffing forces and the rearward slots therein elongated forwardly only, beyond the normal position of the cooperating key, to permit said key to move forwardly on 40 draft, an amount sufficient to correspond with the desired compression of the front cushioning device.

5. In railway draft rigging, in combination with 45 railway vehicle framing, a drawbar, a plurality of friction cushioning devices, common housing means forming a friction element of said devices, yoke-acting means connected to said drawbar and provided with key slots, a key extending through said slots in said yoke-acting means and 50 slots in said framing and housing means, the slots in said yoke-acting means being elongated only to the rear of the normal position of the key and the slots in the framing being elongated forwardly of the normal position of the key, whereby 55 by said key is stationary when the drawbar is subjected to buffing forces and movable under the action of draft forces.

6. In a railway vehicle, in combination with a 60 back-stop, a drawbar, a yoke, cushioning mechanism embraced by said yoke and comprising a 65

housing, a set of friction elements received in each end of said housing, stop portions normally engaged by the forward portion of said cushioning mechanism and stop means limiting rearward movement only of the housing from normal position so that the friction elements in the front end only are actuated on buff, said mechanism normally engaging said yoke and said yoke normally engaging said backstop, said backstop having abutment portions extending forwardly therefrom and normally engaging said housing, whereby said housing and yoke are both held against relative movement when the cushioning mechanism is subjected to buffing forces.

7. In a railway vehicle, in combination with 15 longitudinal framing portions provided with slots, a drawbar, yoke-acting means, backstop means normally engaged by said yoke-acting means, cushioning mechanism comprising a housing with an end opening toward said backstop means, 20 cushioning means disposed in said open end of the housing, said yoke-acting means embracing said cushioning mechanism, said housing having a slot, and a key received in said slot and corresponding slots in said framing portions, said latter slots being elongated forwardly only from the normal position of the key to prevent rearward movement of said housing and actuation of said cushioning means on buff.

8. In a railway vehicle, in combination with 25 draft arms connected by a backstop, a drawbar, a yoke, cushioning mechanism embraced by said yoke and comprising a housing movable with respect to said arms and with a rearwardly opening end providing flaring friction surfaces, cushioning means disposed in said open end of the housing and comprising elements engaging said friction surfaces, stop portions normally engaged by the forward portion of said cushioning mechanism, said cushioning means normally engaging 30 said yoke, and said yoke normally engaging said backstop, said draft arms being connected by a transverse tie portion, said housing having a shouldered portion normally engaging said tie 35 portion for holding said housing against movement with respect to the arms and preventing actuation of said cushioning means when the mechanism is subjected to buffing forces.

9. In a railway vehicle, in combination with 40 draft arms, a drawbar, a yoke, a draft gear embraced by said yoke and comprising a housing member movable with respect to said arms and with open ends, cushioning means received in each end of said housing, a follower engaging the 45 ends of said cushioning means at each end of the gear, stop portions provided on said draft arms and normally engaged by the front follower, the rear follower normally engaging the yoke, said draft arms being connected by a backstop 50 portion normally engaged by said yoke, and abutment portions on said draft arms normally engaging the housing, whereby said housing and yoke are both held against relative movement when the gear is subjected to buffing forces.

10. In a railway vehicle, in combination with a backstop, a drawbar, a yoke, cushioning mechanism embraced by said yoke and comprising a housing, a set of friction elements received in each end of said housing, stop portions normally 55 engaged by the forward portion of said cushioning mechanism, and stop means limiting rearward movement only of the housing from normal position so that the friction elements in the front end only are actuated on buff, said mechanism 60

normally engaging said yoke and said yoke normally engaging said backstop.

11. In railway draft rigging, in combination with draft sills, a drawbar, a plurality of cushioning devices comprising housing means and spring-actuated friction elements disposed between said sills, yoke-acting means extending on either side of said cushioning devices and between said sills, means for operatively connecting the drawbar and yoke-acting means, and a key functioning as rear stop means for the front cushioning device and extending rearwardly of the friction elements of said front device and forwardly of the friction elements of the rear cushioning device, said sills being slotted to receive said key, said slots being elongated forwardly only beyond the normal position of the key, an amount corresponding approximately to the normal movement for full compression of the front cushioning device, to permit said key to move forwardly on draft and prevent rearward movement thereof and actuation of one of said cushioning devices on buff.

12. In railway draft rigging, in combination

with railway vehicle framing, a drawbar, a plurality of cushioning devices comprising housing means and spring-actuated friction elements, yoke-acting means extending on either side of said cushioning devices and between longitudinal portions of said framing, means for operatively connecting the drawbar and yoke-acting means, a front follower for the front cushioning device, means for limiting forward movement of said follower, and a key, normally engaged by the housing means for the front cushioning device so that it functions as a backstop therefor, and extending between said cushioning devices and with its end portions received in slots in said yoke-acting means and said longitudinal portions of the framing, said slots being elongated only forwardly of the normal position of the key, and terminating short of said front follower-limiting means, to allow for forward movement of said devices upon the application of draft forces to said drawbar and prevent rearward movement of said key and actuation of the rearmost cushioning device on buff.

DONALD S. BARROWS.
